UNITED STATES PATENT OFFICE.

ELLSWORTH H. SEBRING, OF SEBRING, OHIO, ASSIGNOR TO THE E. H. SEBRING CHINA COMPANY, OF SEBRING, OHIO, A CORPORATION OF OHIO.

DESIGN FOR A SQUARE BAKER.

Application filed December 2, 1926. Serial No. 19,905. Term of patent 7 years.

To all whom it may concern:

Be it known that I, ELLSWORTH H. SEBRING, a citizen of the United States, residing at Sebring, in the county of Mahoning and State of Ohio, have invented a new, original, and ornamental Design for a Square Baker, of which the following is a specification, reference being had to the accompanying drawing, forming part hereof.

Figure 1 is a plan view of a square baker, showing my new design; and

Fig. 2, a section taken substantially on the line 2—2, Fig. 1.

I claim:

The ornamental design for a square baker, as shown.

ELLSWORTH H. SEBRING.
